AUTOMATIC CHOKE VALVE

Lester E. Perrine, Detroit, Mich., assignor to General Motors Corporation, Detroit, Mich., a corporation of Delaware

Original application March 11, 1935, Serial No. 10,512. Divided and this application December 30, 1940, Serial No. 372,315

13 Claims. (Cl. 123—119)

This invention has to do with mechanisms for automatically operating the choke valves of carburetors of internal combustion engines, and has for its principal object to provide a mechanism, which will without attention on the part of the operator of the engine, adjust the choke valve of the carburetor to the various positions in which it should be while the engine is being started and operated under various conditions.

The invention with which this application, which is a division of my Patent No. 2,226,580, December 31, 1940, is concerned, resides in an automatic choke valve operating mechanism which includes engine intake manifold suction and temperature actuated elements, and whose principal features are extreme simplicity in construction and installation, and a "snap" type thermostat.

For a better understanding of the nature and objects of this invention reference is made to the following specification, in which is described the preferred embodiment of the invention which is illustrated in the accompanying drawing.

In the accompanying drawing:

Figure 1 is a view of automatic choke valve operating mechanism in accordance with my invention installed on an internal combustion engine.

Figure 2 is an enlarged sectional view of the automatic choke valve operating mechanism shown in Figure 1.

In the drawing, the reference character 13 indicates the intake manifold of an internal combustion engine, and the reference character 10 a carburetor which is mounted on the intake manifold. Through the body of the carburetor 10 extends a duct 11, through whose upper end air enters the carburetor, and from whose lower end a combustible mixture of fuel and air is discharged into the intake manifold 13. The portion of the intake manifold into which the combustible mixture enters from the carburetor, is surrounded by a jacket 12, through which exhaust gases from the engine may be circulated to heat the combustible mixture.

In the lower end of the duct 11, there is located a throttle valve 15 of the butterfly type, by which the rate at which the carburetor 10 supplies combustible mixture to the cylinders, and thus the speed of the engine is regulated. The throttle valve 15 is mounted on a shaft 14, which is journaled in the body of the carburetor. To the shaft 14 is fixed an operating lever 62, which is arranged to be actuated by the operator

of the engine through a link 61, a lever 60 and a shaft 23.

In the upper end of the duct 11 there is located a choke valve 17 of the butterfly type, by which the entrance of air into the carburetor, and thus the richness of the combustible mixture which the carburetor supplies to the cylinders of the engine is regulated. The choke valve is mounted on a shaft 16, which is journaled in the body of the carburetor and is unbalanced, so that flow of air into the carburetor tends to open it.

To control the choke valve 17, there is provided mechanism which is carried by a plate 95, which is mounted over and closes an opening 94 in the upper wall of the intake manifold 13, near the jacket 12. On the under surface of the plate 95 there are formed two bosses 97 and 98, which project into the intake manifold 13, and are spaced lengthwise thereof. In a slot 99 in the boss 97, there is seated one end of a strip 100. The other end of the strip 100 extends into a bore 101 in the boss 98, and abuts against a set screw 102, which is threaded into the bore.

The strip 100 is a bimetal one, and consequently a thermostat, and is installed in the slot 99 and bore 101 with the layer of metal with the higher temperature coefficient of expansion on the underside of the layer of metal with the lower temperature coefficient of expansion. The set screw 102 is adjusted so as to make the distance between its inner end and the bottom of the slot 99 in the boss 97 less than the length of the thermostat 100, by an amount sufficient to bow the thermostat considerably. The direction of bow will depend on the temperature of the thermostat, downwardly if the temperature is above a preselected value, and upwardly if the temperature is below the preselected value. By reason of the circumstance that the distance between the abutments of the thermostat 100 is less than the length of the thermostat, the thermostat is a "snap" type device, i. e., a device which moves instantaneously from or to a considerably upwardly bowed to or from a considerably downwardly bowed position upon a change in temperature, from below or above or to above or below the preselected value, and does not occupy any intermediate position except instantaneously. Of course, when bowed either upwardly or downwardly, the thermostat 100 can within limits function as a "gradational" type device and as a spring.

Through the plate 95 midway between the bosses 97 and 98 extends an opening 103, which is sealed by a flexible diaphragm 104, whose

outer margin is clamped between the plate 95, and an annular member 106 which encircles the opening 103. On the upper surface of the annular member 106, there are formed ears 107, through which extends a pin 109, on which one end of a lever 108 is pivotally mounted. The other end of the lever 108 is connected by a link 93 to an arm 25, which is fixed to the shaft of the choke valve 17. Through the center of the flexible diaphragm 104 extends a pin 111, whose lower end is suitably secured to the thermostat 100, and whose upper end is pivotally connected by a pin 112 to the lever 108 between its ends. The hole in the diaphragm through which the pin 111 extends is sealed, and the rod is secured to the diaphragm by discs 113 between which the central portion of the diaphragm is clamped.

When an engine equipped with the choke valve operating mechanism shown in the drawing and hereinbefore described is not operating, the position of the choke valve 17 will depend upon the temperature of the engine. If the temperature of the engine exceeds a preselected value, the thermostat 100 will be bowed downwardly to an extent which depends upon how much the temperature exceeds the preselected value, and will consequently hold the choke valve open to the proper position, for starting the engine at the prevailing temperature. If, however, the temperature of the engine is below the preselected value, the thermostat will be bowed upwardly to an extent which depends upon how much the temperature is below the preselected value and will, consequently, hold the choke valve closed to the proper position for starting the engine under the prevailing temperature.

If the engine is started when its temperature is above the preselected value, the choke valve will, when the engine begins to operate normally under its own power, be opened somewhat farther against the resistance of the thermostat by the flow of air into the carburetor, and intake manifold suction acting on the choke valve, and the flexible diaphragm 104, respectively, and effect the leaning of the combustible mixture supplied by the carburetor to the engine, which is desirable at this time. As the engine warms up heat derived from the combustible mixture flowing past it, and heat conducted through the wall of the intake manifold 13 and the plate 95, will raise the temperature of the thermostat, and gradually bow it farther downwardly, and thus the farther opening of the choke valve, and the consequently further leaning of the combustible mixture, which is desirable under these circumstances will be effected.

If the engine is started when its temperature is below the preselected value, the choke valve will, when the engine begins to operate normally under its own power, be opened somewhat against the resistance of the thermostat by the flow of air into the carburetor, and intake manifold suction acting on the choke valve and the flexible diaphragm, respectively, and effect the leaning of the combustible mixture which is desirable at this time. As the engine warms up heat derived from the combustible mixture flowing past it, and heat conducted through the wall of the intake manifold and the plate 95, will raise the temperature of the thermostat. Increase in the temperature of the thermostat will gradually decrease its upward bow, until the temperature reaches the preselected value, then instantaneously reverse the curvature of the thermostat, and thereafter, gradually bow

the thermostat farther downwardly, and thus the farther opening of the choke valve and the consequent further leaning of the combustible mixture, which is desirable under these circumstances will be effected.

Regardless of the position of the thermostat, whenever the engine is operating under its own power, changes in the rate of flow of air into the carburetor and intake manifold suction acting on the choke valve and the flexible diaphragm, respectively, will move the choke valve somewhat against the resistance of the thermostat, and effect the leaning or enriching of the combustible mixture supplied by the carburetor to the engine which is desirable when such changes occur.

Of course, after the engine has been stopped the choke valve operating mechanism will, by a process which will be clear from what has been said with regard to the operation of the mechanism, continuously maintain the choke valve at the proper position for starting the engine under the existing conditions.

I claim:

1. In an internal combustion engine, a carburetor in which there is incorporated a choke valve, a member with a passage in it which connects the carburetor with a cylinder of the engine, a member which constitutes a closure for an opening in the wall of the first specified member, a thermostat mounted on the second specified member within the mentioned passage, a member which extends through an opening in the second specified member and connects the thermostat with the choke valve, and a flexible member responsive to pressure variations within the mentioned passage which is secured to the third specified member, and seals the opening in the second specified member through which it extends.

2. In an internal combustion engine carburetor, a valve disposed in the main air admission orifice of the carburetor to regulate the entrance of air into the carburetor, and a thermostat which is so constructed and arranged that it moves the mentioned valve abruptly from one position to a substantially different position when the temperature reaches a preselected value.

3. In an internal combustion engine carburetor, a valve disposed in the main air admission orifice of the carburetor to regulate the entrance of air into the carburetor, and a bimetal thermostat of which a portion is bowed and restrained from extension so arranged and connected to the mentioned valve that it moves it abruptly from one position to a substantially different position when the temperature reaches a preselected value.

4. In an internal combustion engine, a carburetor in which there is incorporated a choke valve, a member in which there is a passage which connects the carburetor with a cylinder of the engine and an orifice which communicates with the passage, a closure for the orifice which includes a member responsive to variations in pressure within the mentioned passage connected to the choke valve, and a thermostat disposed within the passage and connected to the second specified member.

5. In an internal combustion engine, a carburetor in which there is incorporated a choke valve which is unbalanced so that flow of air into the carburetor tends to open it, a member responsive to an engine operating condition connected to the choke valve so that it tends to open it when the engine is operating, and a thermo-

stat connected to the specified member and there-through to the choke valve so that it tends to open and close the choke valve when the temperature of the engine rises and falls.

6. In an internal combustion engine, a carburetor in which there is incorporated a choke valve, a member with a passage in it which connects the carburetor with a cylinder of the engine, a member responsive to pressure variations within the mentioned passage connected to the choke valve so that it tends to open it when the pressure in the passage falls, and a thermostat connected to the second specified member and therethrough to the choke valve so that it tends to open and close the choke valve when the temperature of the engine rises and falls.

7. In an internal combustion engine, a carburetor which includes a choke valve and a throttle valve, a member with a passage in it which connects the carburetor with a cylinder of the engine, and means for regulating the position of the choke valve which includes a thermostat disposed within the mentioned passage on the engine side of the throttle valve and connected to the choke valve so that it may move it.

8. In an internal combustion engine, a carburetor which includes a choke valve and a throttle valve, a member with a passage in it which connects the carburetor with a cylinder of the engine, means for heating combustible mixture passing through the mentioned passage from the carburetor to the engine, and means for regulating the position of the choke valve, which includes a thermostat disposed within the mentioned passage on the engine side of the throttle valve and the first specified means so that it is heated by the combustible mixture heated by the first specified means.

9. In an internal combustion engine, a member including a carburetor, with a passage in it through which air travels from the atmosphere to a cylinder of the engine, a choke valve in the carburetor, and means for regulating the position of the choke valve, which includes a thermostat disposed within the mentioned passage, and a member responsive to variations in pressure within the mentioned passage connected to the choke valve so that they may move it.

10. In an internal combustion engine, a carburetor in which there is incorporated a choke 50

valve, a member in which there is a passage which connects the carburetor with a cylinder of the engine, and an orifice which communicates with the passage, a closure for the orifice which 5 includes a member responsive to variations in pressure within the mentioned passage connected to the choke valve, and a thermostat so constructed and arranged that it moves abruptly from one position to a substantially different 10 position, when the temperature reaches a pre-selected value, disposed within the passage and connected to the second specified member and there-through to the choke valve.

11. In an internal combustion engine, a member 15 including a carburetor, with a passage in it through which air travels from the atmosphere to a cylinder of the engine, a choke valve in the carburetor, and means, including a member and a thermostat, for regulating the position of the 20 choke valve, the member being responsive to variations in pressure within the mentioned passage and the thermostat being so constructed and arranged that it moves abruptly from one position to a substantially different position when 25 the temperature reaches a preselected value.

12. In an internal combustion engine, a member, including a carburetor, with a passage in it through which air travels from the atmosphere to a cylinder of the engine, a choke valve in the carburetor, and means for regulating the position of the choke valve which includes a thermostat so constructed and arranged, that it moves 30 abruptly from one position to a substantially different position, when the temperature reaches 35 a preselected value, disposed within the mentioned passage.

13. In an internal combustion engine, a member, including a carburetor, with a passage in it through which air travels from the atmosphere to a cylinder of the engine, a choke valve in the carburetor, and means for regulating the position of the choke valve which includes a member 40 responsive to variations in pressure within the mentioned passage, and a thermostat so constructed and arranged, that it moves abruptly from one position to a substantially different position, when the temperature reaches a pre-selected value, disposed within the mentioned 45 passage.

LESTER E. PERRINE.
